UNITED STATES PATENT OFFICE.

ANDREW CLINTON LONG, OF DEMUND, KENTUCKY.

PEAVEY.

No. 919,044.

Specification of Letters Patent.

Patented April 20, 1909.

Application filed June 15, 1908. Serial No. 438,674.

To all whom it may concern:

Be it known that I, ANDREW CLINTON LONG, a citizen of the United States, residing at Demund, in the county of Morgan and

5 State of Kentucky, have invented a new and useful Peavey, of which the following is a specification.

The present invention has reference to improvements in peavies, and it aims chiefly to 10 provide an exceedingly simple, inexpensive, and effective implement of that type in which the hook is carried by a pivoted sleeve in whose bore the stem of the hook is slidably fitted, so as to be capable of adjustment for 15 use in connection with large or small timbers.

More especially, the invention resides in the specific construction of the hook stem and the sleeve above referred to, and in the 20 particular retaining devices employed for engagement with said stem.

The preferred embodiment of the invention is illustrated in the accompanying drawings in which corresponding parts are designated by the same reference characters 25 throughout the several views.

Of the said drawings:—Figure 1 is a side elevation of the improved peavey. Fig. 2 is a view at right angles to Fig. 1. Fig. 3 is a detail view showing the hook in one position, 30 the sleeve and the bill of the hook appearing in section. Fig. 4 is a view similar, in the main, to Fig. 3, but showing the hook in its other position.

Referring more particularly to the drawings, 1 designates the handle, 2 the ferrule, and 3 the spur of a peavey of the ordinary type, these elements requiring no extended description. The ferrule, however, is formed adjacent its upper end with a pair of spaced 40 ears 4 between which is fitted an ear 5 formed upon the upper end of a sleeve 6, the three ears being provided with alining perforations arranged to receive the bolt 7 by means of which the sleeve and the ferrule are joined 45 together.

The bore 8 of the sleeve opens out through the lower end thereof, and is arranged to receive the stem 9 of the hook, whose bill portion 10 is enlarged at its free end, as indicated by the numeral 11. This enlarged portion extends above and below the bill and is formed with a longitudinal passage 12 in which a spur 13 is slidably fitted, said spur being retained in position by a thumb-screw

14 whose stem fits in an opening formed in 55 the lower portion of the enlargement 11 and has its inner end arranged to impinge against the spur.

The outer face of the sleeve is formed with a pair of alining longitudinal slots 15 and 16 which open into the bore 8. Upon opposite sides of the upper slot 15 is formed a pair of laterally-projecting spaced ears 17, while upon opposite sides of the lower slot 16 are formed a pair of similar ears 18, the height of 60 the last-mentioned ears being less than that of the ears 17, and the length of the slot 16 less than that of the slot 15. Both pairs of ears are provided with alining openings 65 designed to receive pins 19 and 20 upon which 70 pawls 21 and 22 are pivoted, the first-mentioned pawl including a forwardly extending finger 23, and a centrally-located lateral finger 24.

The finger 24 of the pawl projects through 75 the slot 15 into a longitudinal seat 25 formed in the adjacent face of the stem portion of the hook, into which seat the finger 23 is likewise caused to project under the influence of an expansible coil-spring 26, which bears 80 against the under side of the finger-piece of the pawl, when the stem has been moved to its farthest extent within the sleeve bore, as shown in Fig. 3, in which position the seat 25 and the slot 15 register with each other. 85 The pawl 22 has its free upper end terminating in a lateral tongue 27 which is caused to project normally through the slot 16 by means of an expansible coil-spring 28 which bears against the finger-piece of this pawl. 90

When the hook is at the limit of its inward movement it is held against displacement by the finger 23 of the upper pawl which contacts with the upper end wall of the seat 25. When so adjusted, the implement is designed for lifting relatively small timbers. 95 To permit large timbers to be raised, the finger-piece of the pawl 21 is depressed, thus withdrawing the finger 23 from the seat, whereupon the hook may be moved outwardly of the sleeve until the finger 24 contacts with the upper end wall of the seat, the tongue 27 being free to move through the slot 16 into contact with the lower end wall of the seat, thus holding the hook against 105 further outward movement.

It will likewise be understood that an adjustment of the spur 13 is possible, owing to

its disposition in the passage 12, the screw 14 being utilized to retain said spur in adjusted position.

What is claimed, is:—

- 5 1. In a peavey, the combination, with a handle, of a sleeve pivoted to the handle and formed with a longitudinal slot; a hook having its stem slidably fitted in the bore of the sleeve and formed with a longitudinal seat located directly opposite said slot; and means 10 carried by the sleeve, and arranged to extend through said slot into said seat, to retain the hook in adjusted position.
- 15 2. In a peavey, the combination, with a handle, of a sleeve pivoted to the handle and formed with a pair of alining longitudinal slots; a hook having its stem slidably fitted in the bore of the sleeve; and a pair of spring-pressed members carried by the sleeve and arranged to extend through said slots into engagement with said stem, to retain the hook in adjusted position.
- 20 3. In a peavey, the combination, with a handle, of a sleeve pivoted to the handle and formed with a pair of alining longitudinal slots; a hook having its stem slidably fitted in the bore of the sleeve; and a pair of spring-pressed members carried by the sleeve and arranged to extend through said slots into engagement with said stem, one of said 25 members being adapted to hold the hook at the limit of its inward movement, and the

other member to hold the hook at the limit of its outward movement.

4. In a peavey, the combination, with a handle, of a sleeve pivoted to the handle and formed with a longitudinal slot; a hook having its stem slidably fitted in the bore of the sleeve and formed with a longitudinal seat; and a spring-pressed member carried by the sleeve and formed with a pair of fingers arranged at an angle to each other and adapted to extend through said slot into said seat, one of said fingers being adapted to contact with the upper end wall of said seat, to hold the hook at the limit of its inward movement, and the other finger to contact with said wall, to hold the hook at the limit of its outward movement.

5. In a peavey, the combination with a handle; of a sleeve pivoted to the handle and formed with a longitudinal slot; a hook having its stem slidably fitted in the bore of the sleeve, and its bill portion terminating in an enlargement formed with a longitudinal passage; a spur slidably fitted in said passage; means for retaining the spur in adjusted position; and means carried by the sleeve and arranged for engagement with said stem, to hold the hook in adjusted position.
